UNITED STATES PATENT OFFICE.

CHARLES E. MORRIS, OF LEAVENWORTH, KANSAS, ASSIGNOR OF ONE-HALF TO
CHARLES W. PARKER, OF LEAVENWORTH, KANSAS.

MOTOR-OPERATED VEHICLE.

1,320,336.

Specification of Letters Patent.

Patented Oct. 28, 1919.

Application filed July 2, 1917. Serial No. 178,313.

To all whom it may concern:

Be it known that I, CHARLES E. MORRIS, a citizen of the United States, residing at Leavenworth, in the county of Leavenworth and State of Kansas, have invented a certain new and useful Improvement in Motor-Operated Vehicles, of which the following is a specification.

My invention relates to improvements in 10 motor operated vehicles.

One of the objects of my invention is to provide novel means by which the direction of movement of an electrically operated vehicle may be automatically reversed whenever the circuit in which the vehicle motor is included is closed and then opened.

A further object of my invention is to provide novel means for indicating to a distant operator the direction in which the 20 vehicle is traveling.

Still another object of my invention is the provision of novel means for operating a reversing switch.

Other novel features of my invention are 25 hereinafter fully described and claimed.

In the accompanying drawings which illustrate the preferred embodiment of my invention,

Figure 1 is an elevation of a car provided with my improvement.

Fig. 2 is a bottom view of the same, some of the parts being shown in horizontal section.

Fig. 3 is a diagrammatic view of a portion of the electric circuit employed when utilizing a continuous current.

Fig. 4 is an enlarged vertical sectional view of the contact mechanism employed for taking the current from the wheel of the 40 car.

Fig. 5 is an enlarged vertical sectional view on the line 5-5 of Fig. 6 of the reverse switch and mechanism for operating the same.

Fig. 6 is a bottom view of what is shown in Fig. 5.

Fig. 7 is a vertical sectional view on the line 7-7 of Fig. 5.

Fig. 8 is a side elevation of a portion of 50 the reversing switch.

Fig. 9 is an enlarged view, partly in side elevation and partly in vertical section of a portion of the reversing switch operating bar and parts connected therewith.

Fig. 10 is a diagrammatic view of a portion of the electric circuit such as is employed when either the alternating or continuous current is utilized.

Fig. 11 is a diagrammatic view of a portion of the circuit employed when the alternating current is utilized.

Fig. 12 is a view partly in elevation and partly in vertical section of one of the rheostats, and parts connected therewith.

Fig. 13 is an enlarged vertical sectional view on the line 13-13 of Fig. 12.

Fig. 14 is an enlarged horizontal section on the line 14-14 of Fig. 12.

Similar reference characters designate similar parts in the different views.

1 designates a car body provided with car wheels 2 adapted to run on rails 3 and which are secured to an axle 4 having secured to it a gear wheel 5 which meshes with a pinion 6 secured to the armature shaft 7 of a 75 motor 8 carried by the car body 1.

The inner side of each wheel 2 is provided with a metal contact plate 9 which is in electrical contact with a steel tire 10, Fig. 2, which bears upon the adjacent rail 3.

Longitudinally slidably respectively in two horizontal transverse tubes 11 are two contact pins 12 which are respectively normally forced against the plates 9 by two coil springs 13 respectively mounted in the 85 tubes 11 and which respectively bear at their inner ends against two screws 14 adjustably mounted in the inner ends of the tubes 11. The latter are respectively supported in bearings 15 which are secured to the under 90 side of the car body 1.

Secured to the under side of the car body 1 is a reversing switch mechanism comprising the following described parts.

A horizontal plate 16, of insulating material, is secured to the under side of the body 1 and has secured to it two downwardly extending supporting members 17, Figs. 5 to 7, in which is oscillatably mounted a horizontal transverse shaft 18 to which is 100 secured a flat rectangular block 19, of insulating material, which has mounted upon it two contact plates 20 and 21.

Secured to the plate 16 at one side of the oscillatable contact carrying block or member 19 are two spring contact plates 22 and 23, which are always respectively in contact with the plates 20 and 21. Also secured

to the plate 16 are two spring contact plates 24 and 25, which are adapted to respectively bear upon the contact plates 20 and 21 when the contact carrying member 19 is swung to one position, and which are adapted to slide off from said contact plates, when the contact carrying member 19 is swung to the position shown in Figs. 3, 5 and 11.

Secured to the plate 16 at the opposite side of the member 19 are two spring contact plates 26 and 27 which are adapted to respectively bear against the contacts 20 and 21 when the member 19 is in the position shown in Figs. 3 and 5, and which are adapted to slide off from said contacts when the member 19 is rocked to the position shown in dotted lines in Fig. 5.

For the purpose of oscillating the contact carrying member 19, a solenoid is provided comprising a helix or winding 28 secured to the plate 16, and having reciprocative therein a magnetizable core 29 which is secured to one end of a horizontal oscillatable member comprising a bar 30 which is slidably mounted in a hole provided in a bracket 31 depending from the plate 16. The bar 30 is provided with a longitudinal slot 32 through which extends the shaft 18.

Pivoted by a horizontal screw 33 to the bar 30 is an arm or member 34, Fig. 5, which is yieldingly held in the horizontal longitudinal position by a vertical spring 35 having at its lower end a recess 36 which has mounted in it one end of the arm of member 34. The upper end of the spring 35 is secured to a plate 37 attached to the bar 30. The other end of the arm 34 is adapted to enter either of two notches 38 and 39 provided in one end of a plate 40 which is rigidly secured to the adjacent end of the block or member 19.

A U-shaped plate 41 which is secured to the bar 30, Fig. 5, has its arms arranged to engage and limit the oscillating movement of the block or member 19.

When the helix or winding 28 is energized, the core 29 will be drawn therein, thus sliding to the right, as viewed in Fig. 5, the bar 30. The arm 34, with the parts as shown in solid lines in Fig. 5, will enter the notch 38 and swing the plate 40 and member 19 to the position shown in dotted lines in Fig. 5, thus rocking the member 19 so that the contact springs 26 and 27 will slide onto the contact plates 20 and 21, and the contact springs 24 and 25 will slide off from said contact plates, thus reversing the direction of the current passing through the motor 8, as will shortly be described.

For the purpose of yieldingly holding the plate 40 and member 19 in its two operative positions, there is provided an upright spring 42, Fig. 5, the upper end of which is secured to the plate 16 and the lower end of 65 which is provided with a lateral V-shaped

projection 43, which is adapted to bear against the two oblique edges of a V-shaped projection 44 which is provided at the end of the plate 40 opposite to the end containing the notches 38 and 39.

For restoring the core 29 and bar 30 to the position shown in solid lines in Figs. 5 and 6, an upright spring 45 has its upper end secured to the plate 16 and has its lower end bearing against the right side of the screw 33, as viewed in Figs. 5 and 6. By reason of the employment of the spring 45 for restoring the core 29 and bar 30 to the initial position, shown in solid lines in Figs. 5 and 6, after the core has been energized 80 and then deenergized, such restoration of the core will be effected regardless of its position with respect to the horizontal, as, for example, when the vehicle is on a steep grade, when the vehicle which is controlled 85 by the reversing mechanism is an automobile, or, in case the vehicle is an aeroplane, when the latter is in other than a horizontal position.

When a continuous current is employed, 90 the circuit arrangement shown in Fig. 3 is used. As shown in this figure, a conductor 46 connects one end of the helix 28 with one of the screws 14, the other screws 14 being connected by a conductor 47 with one 95 end of the winding 48 of one of the field magnets of the motor 8, the other end of said winding being connected by a conductor 49 with the contact spring 22. The other end of the helix 28 is connected by a conductor 50 with one end of the winding 51 of the other field magnet of the motor 8. The other end of the winding 51 is connected by a conductor 52 with the contact spring 23.

The contact springs 24 and 25 are respectively connected by conductors 53 and 54 with the two brushes of the motor 8.

A conductor 55 connects the contact springs 24 and 27, and a conductor 56 connects the contact springs 25 and 26.

With the parts as shown in Fig. 3, and assuming the lower rail 3 to be the feed rail, when the current is turned on, it will pass from said rail through the adjacent wheel 2, contact pin 12, coil spring 13 and screw 14, thence through conductor 46, helix 28, conductor 50, winding 51, conductor 52, contact plates 23, 21 and 27, conductor 55, contact spring 24, conductor 53, motor 8, conductor 54, contact plate 25, conductor 56, 110 contacts 26, 20 and 22, conductor 49, winding 48, conductor 47 and the other screw 14, spring 13, and pin 12, to the opposite wheel 2 and thence to the return rail 3.

The helix 28 will be energized, thus drawing in the core 29 and pulling the bar 30, so that the arm 34 enters the notch 38, thus reversing the switch to a position in which the contacts 24 and 25 will rest on the plates 20 and 21 and the contacts 26 and 27 will 120

pass off from said plates 20 and 21. The current will now pass from the feed rail 3 through the helix 28 to the contact plate 21, as above described. The current will 5 now pass through the motor 8 in the reverse direction to that above described, passing from the plate 21 through the contact 25, conductor 54, motor 8, conductor 53, contact 24, contact plate 20, contact 22, and thence 10 to the return rail 3 as above described. The car will now run in one direction. To reverse its movement, it is but necessary to shut off the current from the feed rail 3, upon which the helix 28 will be deenergized, 15 thus permitting the spring 45 to retract the bar 30. If now the current be again turned on, the helix 28 will be energized, thus drawing in the core 29 and moving the bar 30 so that the arm 34 will enter the notch 39 and 20 thus swing the plate 40 and member 19 to the original position as shown in solid lines in Fig. 5, and as shown in Fig. 3, in which case the current will pass through the motor 8 by the path first described, thus reversing 25 the motor and reversing the direction of movement of the car.

When an alternating current is to be used, the circuit employed is that shown in Fig. 11. This circuit is the same as that shown 10 in Fig. 3, excepting that the helix 28 is not in series with the motor 8 but is in a shunt circuit.

Referring to Fig. 11, one end of the helix 28 is connected by a conductor 57 with the conductor 47. The other end of the helix 28 is connected by a conductor 58 with a conductor 59 which connects one end of the winding 51 with the adjacent screw 14.

The current will now pass from the feed rail 3 to the adjacent screw 14, as already described, and thence through the conductor 59 to the winding 51, from which it will pass through the reversing switch and motor 8 to the return rail 3 as already described. A portion of the current will pass from the conductor 59 through the conductor 58, helix 28 and conductor 57 to the conductor 47 from which it will pass as already described to the return rail 3. The 15 reversing of the movement of the car will be effected upon the shutting off and turning on of the current in the manner already described.

In Fig. 10 is shown a circuit arrangement 55 to be employed in connection with either of the circuit arrangements shown in Figs. 3 and 11. In Fig. 10, two tracks are shown and two circuit controlling mechanisms to be used respectively in conjunction therewith. A description of one track and controlling mechanism will suffice, as both are alike. Each track has a feed rail 3 and a return rail 3'. The tracks are endless tracks

disposed parallel with each other so that the cars on each track may race with cars on the other track.

Referring particularly to Figs. 10 to 14, 60 designates the operating lever of a rheostat having the usual resistance coils 61 which are connected by a conductor 62 with one of the feed rails 3. The return feed rail 3' is connected by a conductor 63 with the movable contact 64 of a variable resistance having a resistance coil 65 coöperating in the usual manner with the movable contact 64 and connected by a conductor 66 with a contact 67 of a knife switch having a U-shaped lever provided with two arms 68 and 69 insulated from one another and respectively pivoted to two posts 70 and 71 which are respectively connected by conductors 72 and 73 with a return wire 74 and a feed wire 75 of the circuit which supplies the current.

The arm 69 is adapted to engage a contact 76 which is connected by a conductor 77 with the operating lever 60 of the rheostat.

When the switch arms 68 and 69 are in the closed position shown, and the rheostat lever 60 is in the operative position shown, 90 the current will pass from the feed wire 75 through the conductor 73, post 71, arm 69, contact 76, conductor 77, lever 60, coils 61, conductor 62 to the feed rail 3, thence through the solenoid helix 28, reversing 95 switch and motor 8, as hereinbefore described, to the return rail 3', from which the current will pass by the conductor 63, contact 64, coil 65, conductor 66, contact 67, arm 68, post 70 and conductor 72 to the return wire 74.

By throwing the operating lever 60 from the operative to the neutral position and then again to the operative position, the knife switch being closed, the reversing 105 switch on the car will be operated to reverse the current through the motor 8, thereby reversing the direction of movement of the car, as above described.

In order that the operator may know 110 whether the particular car controlled by the rheostat lever 60 is going forward or backward, the following described indicating mechanism is provided.

Referring particularly to Figs. 12 to 14, 115 78 designates the rheostat casing, which has pivoted to its inner wall a pawl 79, which is adapted to consecutively engage the peripheral teeth of a ratchet wheel 80, which is secured to a shaft 81, which is rotatably 120 mounted in a casing 82 carried by the lever 60.

Also secured to the shaft 81 is a wheel 83 provided on its periphery with a circular row of letters, in which the letters F and B 125 alternate with each other and which indicate

respectively whether the car indicated by this device is moving forwardly or backwardly. The letters F and B are adapted, when the ratchet wheel 80 and wheel 83 are 5 rotated step by step, to consecutively appear at an observation opening 84 which is provided in the periphery of the casing 82.

Whenever the lever 60 of the rheostat is moved from the closed or operative position, 10 to the neutral position, the pawl 79 will engage a tooth in the ratchet wheel 80 and turn the latter and the wheel 83 forward one step, so that the next letter on the wheel 83 will appear at the observation opening 84. If 15 the car has been moving forwardly, the letter F will appear at the observation opening. If now the lever 60 is thrown to the neutral position, the wheel 83 will be advanced one step and the letter B will appear at the ob- 20 servation opening 84, indicating that as soon as the rheostat lever 60 is swung from the neutral to the operative position, the motor of the particular car controlled by the lever, or the cars, if there are more than one on the 25 same track, will be operated to reverse the movement of the car.

A plurality of cars, if desired, equipped as above described, may be operated upon each track, and there may be as many tracks 30 as desired.

A knife switch 85 similar to the one just described respectively connects the wires 75 and 74 with conductors 86 and 87. The conductor 87 is connected to a resistance coil 35 88 operatively connected with a movable contact 89 which is connected to the conductor 63. The conductor 86 is connected with a rheostat lever 90 similar to the lever 60 and adapted to coöperate with resistance coils 91 40 which are connected by a conductor 92 with the outer rail of the outer track which corresponds to the rail 3 and is designated by 93. The inner rail 94 of the outer track, corresponds to the rail 3' and is connected to the 45 conductor 63. The operation of the mechanism just described is the same as that of the mechanism which includes the lever 60.

I do not limit my invention to the structure shown and described, as modifications, 50 within the scope of the appended claims, may be made without departing from the spirit of my invention.

What I claim is:—

1. In a motor operated vehicle, an electric 55 motor, an electric circuit including said motor and a reversing switch, vehicle propelling means actuated by said motor, and automatic means rendered effective upon the turning-on of the current in said circuit for 60 operating said switch.

2. In a motor operated vehicle, an electric circuit including a motor and a reversing switch, vehicle propelling means actuated by said motor, and automatic means includ-

ing an electro-magnetic device in said circuit 65 for operating said switch.

3. In a motor operated vehicle, an electric circuit including a motor and a reversing switch, vehicle propelling means actuated by said motor, and automatic means, includ- 70 ing a solenoid having a core and a winding, the latter being included in said circuit, for operating said switch.

4. In a motor operated vehicle, a vehicle, an electric circuit including a motor and a 75 reversing switch carried by the vehicle, means actuated by the motor for propelling the vehicle, and automatic means carried by the vehicle for operating said switch and rendered effective upon the turning of the 80 current off and then on in said circuit.

5. In a motor operated vehicle, a vehicle, an electric circuit including a motor and a reversing switch carried by said vehicle, means actuated by the motor for propelling 85 the vehicle, and automatic means, including an electro-magnetic device carried by said vehicle, said device being in circuit with said switch, for operating said switch.

6. In a motor operated vehicle, a vehicle, an electric circuit including a motor and a reversing switch carried by said vehicle, means actuated by the motor for propelling the vehicle, and automatic means carried by the vehicle and including a solenoid having 90 a core and a winding, the latter being included in said circuit, for operating said switch.

7. In a motor operated vehicle, a vehicle, an electric circuit including a motor and a 100 reversing switch, vehicle propelling means actuated by said motor, automatic means rendered effective upon the turning-on of the current in said circuit for operating said switch, means for opening and closing said 105 circuit, and means operated by said opening and closing means for indicating the direction of movement of said vehicle.

8. In a motor operated vehicle, a vehicle, an electric circuit including electrically op- 110 erated means for running said vehicle, automatically actuated means by which the direction of movement of the vehicle will be reversed, when said circuit is opened and then closed, means for opening and closing said 115 circuit, and means actuated by said opening and closing means for indicating the direction of movement of said vehicle.

9. A plurality of vehicles, an electric cir- 120 cuit, electrically operated means actuated by the current in said circuit for propelling said vehicles independently of each other, and means, automatically actuated upon the cutting off and turning on of the current supplied to any one of said vehicles, by which 125 the direction of movement of the vehicle will be reversed.

10. An electric circuit having a plurality

of branches, motors in said branches respectively, a plurality of vehicles respectively carrying and driven by said motors, means for shutting off and turning on the current in each of said branches independently of the other branches, and means for auto-

matically reversing the direction of the current passing through said motors when the current is shut off and then turned on.

In testimony whereof I have signed my name to this specification.

CHARLES E. MORRIS.
